UNITED STATES PATENT OFFICE.

WILLIAM H. WIGGINS, OF NEW YORK, N. Y., ASSIGNOR TO THE BRUNS-WICK-BALKE-COLLENDER COMPANY, OF NEW YORK, N. Y., A CORPORATION OF OHIO.

BOWLING-ALLEY.

SPECIFICATION forming part of Letters Patent No. 722,340, dated March 10, 1903.

Application filed January 5, 1903. Serial No. 137,775. (No model.)

To all whom it may concern:

Be it known that I, WILLIAM H. WIGGINS, of Brooklyn borough, New York city, in the State of New York, have invented a new and useful Improvement in Bowling-Alleys; and I do hereby declare that the following is a full, clear, and exact description of the same, reference being had to the accompanying drawings, forming part of this specification.

10 My invention relates wholly to those parts of an alley commonly known and designated as the "ball return-way" of the alley—that is, the track or runway on which the bowled balls are returned from the pit end to the 15 players' end of the alley for reuse—and the "side buffers," arranged at either side of the pin-platform of every modern alley-bed. Previous to my invention these ball return-ways had been constructed in a variety of ways, 20 and always, of course, so that a ball placed on the pit end of the ball-track would descend or roll by gravity, thence downwardly and along toward and onto the "terminal" of the return-way located at the players' end 25 of the alley; but in all constructions of return-ways heretofore made the ball-track has always been supported by means of some sort of metallic or other vertical supports arranged at intervals on top of the stringer- 30 beam or partition-strip, which usually runs either at the side of one or between a pair of alleys and usually on top also of a side buffer of the alley, said ball-track being properly secured in some manner to the upper ends of 35 such supporting devices, commonly denominated "irons," and prior to my invention the side buffer, which is a sort of heavy hardwood partition or wall located one at each side of the alley-bed at the vicinity of the "pin- 40 platform," has always been constructed to extend upwardly a little higher than the upper ends of the spotted pins, the irons or supports for that portion of the ball return-way that is located over or near said side buffer 45 projecting upwardly from the top of the said side buffer. In the more approved or latest styles of bowling-alleys these ball return-ways have had the greater portion of their lengths supported a comparatively short dis-

tance above the said stringer-beam or partition-strip, and hence above the level of the alley-ballways, so as to obstruct as little as possible a fair view by spectators at the sides of the alleys of the games being bowled on the latter. However, the said vertical supporting devices or irons (of a greater or less height) have always been necessary to the construction of the return-way, and of course these supporting devices have necessarily been somewhat longer or higher at the 55 inclined pit-end portion of the return-way than elsewhere, so that even under the latest or most approved construction the ball-tracks have been liable to soon get out of order or lose their perfection or rigidity of position on 60 account of the practical impossibility of having these vertical supports (either made of wood or metal, although the latter is most always used) made sufficiently strong to maintain their original positions. Furthermore, this construction of return-way of 65 course involves, necessarily, considerable expense in the manufacture and use, in the manner explained, of these supporting devices or irons.

In the use of alleys having the side buffers made as heretofore it has been found in practice and with the advance of the expertness in the sport or game of bowling, first, that the height of the side buffer proves 70 inadequate to serve all the purposes of the expert bowler, since the latter oftentimes is unable to cause a pin forcibly stricken by his ball to be deflected properly by the side buffer to effectuate the design or object of his 75 stroke, and, second, that a pin which may have been stricken very forcibly by an athletic bowler will fly over the top of the side buffer, often interfering with the game being played on an adjoining alley and sometimes inflicting serious bodily injury on the pit-boy of another alley, and experience has demonstrated that it is practically impossible to effectuate a rigid and durable maintenance 80 in place of those irons which are arranged 85 at the vicinity of and on the side buffer, since at the pit-end portion of the return-way the throwing into the cage or onto the trough of 90 95

the balls partially sidewise by the pit-boys soon weakens the return-way structure at this locality.

My present invention has for its object, first, to dispense with all the return-way irons or separate ball-track supports usually located between the terminal and the extreme pit end of the runway, while at the same time producing a more rigid and durable ball-track located as low down as possible for the greater part of its length, and, second, to overcome the evil of the pit-end portion of the return-way soon getting shackelly and out of repair, while at the same time rendering the side buffer more efficient in action and wholly preventing any flying of a pin from one alley to another and endangering the pit-boys.

To these main ends and objects my invention may be said to consist in a novel construction in which the ball-track or the rails of the ball return-way is or are during the long low-down horizontal portion mounted directly on and securely fastened to a stringer-beam of the alley, in which the side buffer is extended upward sufficiently to have combined directly with it the inclined pit-end portion of the said ball-track and in which the latter is mounted directly on and securely fastened to the top of the side buffer, all as will be hereinafter more fully explained and as will be most particularly pointed out in the claim of this specification.

To enable those skilled in the art to make and use bowling-alleys involving either partially or wholly my invention, I will now proceed to more fully describe the latter, referring by letters to the accompanying drawings, which form part of this specification, and in which I have shown my said invention carried into effect in that precise form in which I have so far very successfully and very extensively practiced it, though mere modifications of form and detail may of course be made without departing from my said invention so long as the construction involves the essential characteristics herein shown and described.

In the drawings, Figure 1 is a perspective view of a pair of bowling-alleys built according to my invention. Fig. 2 is a detail vertical cross-section, on an enlarged scale, taken at the dotted lines 2 2 of Fig. 1. Fig. 3 is a detail vertical cross-section, on the same scale as Fig. 2, taken at the line 3 3 of Fig. 1, and in the several figures the same parts will be found always designated by the same reference-letters.

A and B are respectively the ballways, while C is the back end or swinging buffer-support of an ordinarily-constructed pair of modern alleys having the balk-lines located, as usual, at f f and being provided with the usual newel-post at a for the proper support of the players' end of the ball-terminal and lower terminal-rack, lettered, respectively, b and c, while F F are the usual swinging buffers at the rear of the alley-pits, and D D

are the two outer side buffers, and E the intermediate or middle side buffer, the latter of which, as shown, has mounted directly on it and fastened securely thereto the rails of the pit-end portion (or "sweep," as it is generally called) i of the ball track or return-way. This ball-track, as will be readily seen, after descending at its sweep portion i passes rearwardly in a horizontal direction at h until it about reaches the locality of the balk-lines f f, from which, by preference, it slopes upwardly, as seen at g, and then runs horizontally to the newel-post, said latter horizontal portion constituting the terminal b, heretofore alluded to, and during all the horizontal portion h of the track it is securely fastened in place both to the floor of the alley and to an intermediately-arranged piece or pieces m, as best seen at Fig. 3, where it will also be observed that on either side of the ways h h of the return-way are located the usual ball-gutters G of the alleys, all of these parts being securely fastened together and to the floor of the alley-room in any proper and substantial manner.

At Fig. 3 I have illustrated by a dotted circle the position occupied by one of the largest-sized balls while traveling homeward on the low-down horizontal portion h of the return-way, and by a smaller dotted circle one of smallest-sized or "pony" balls, also traveling homeward or to the players' end of the alley, which pony-ball, however, does not (like the larger one) pass up the upgrade g and thence onto the terminal b of the return-way, but passes through a yoke, in or enlargement of the space between the ways of the return-way, where the inclined portions g merge into the horizontal portion h, and continues rolling rearwardly along and remains on the rearmost portion thereof or on the rack c, all as plainly illustrated in Fig. 1, the construction I have shown thus involving this sort of separation of the larger from the smaller balls being one in common use well known to those skilled in the art and heretofore invented and patented by myself. It will be understood, however, that this preferable form and arrangement of the parts of the return-way are not at all peculiar to my present invention, the essence of which lies in having the horizontal track-rails h, as well as the rearward obliquely-ascending portions or the sweep i, placed directly on and securely fastened, respectively, to the floor or stringer-beams, or both, of an alley or pair of alleys and to either the top of the intermediate side buffer of a pair of alleys or to the top portion of one of the side buffers of a single alley, whereby, as heretofore remarked, not only do I produce a return-way more stable, more economical to manufacture, and more desirable in all other structural qualities than any heretofore made, but one in which while all vertically-arranged supporting devices are dispensed with the long substantially horizontal portion of the return-way or ball-track

may be placed as close to the level of the floor and ballways as may be desired and as may be possible without any conflict between a mis-played ball which may be rolling down one of the "ball-gutters" and a home-coming ball on the return-way, thus producing a construction of bowling-alley in which the ball return-ways do not in the least interfere with the perfect view of the games progressing on the ballways, no matter how many of the latter nor how many return-ways may be involved in the bowling-alley or bowling-alley room in which my invention may be used, and whereby, furthermore, I provide for use a bowling-alley structure in which the side buffer is rendered more efficient as an operative element of the alley, while at the same time rendered capable of preventing the flying of a pin from one alley to another to the detriment of the game and to the possible injury of a pit-boy.

The detailed construction of the side buffer device, which permits an easy, permanent, and economical direct combination therewith of the pit-end portions or sweep of the ball-tracks, may be varied in the discretion or

judgment of the skilled constructor, though the precise form which I have shown and which is best seen at Fig. 3 I have found to be admirable in the practical use of my invention. 30

What I claim, broadly, as my invention, and desire to secure by Letters Patent, is—

In a bowling-alley, the combination, with the usual bed, or ballway, and pit, of a side 35 buffer which extends upwardly to the elevation at which the "sweep," or pit-end portion, of the ball return-way must be located; and a ball return-way having its "sweep," or inclined pit-end portion, mounted directly on, 40 and permanently secured to the top of said upwardly-extended side buffer, and having its lowermost main, horizontal portion mounted directly on the floor, or stringer-beam of the alley; all in substantially the manner and 45 for the purposes hereinbefore set forth.

In witness whereof I have hereunto set my hand this 29th day of November, 1902.

WM. H. WIGGINS.
